THERAPEUTIC DEVICE

Arthur C. Kleckner, Racine, Wis.

Application April 21, 1934, Serial No. 721,684

6 Claims. (Cl. 128—401)

This invention relates to therapeutic devices, more particularly to therapeutic devices of the type in which fluid is maintained at a desired temperature and caused to circulate through a bag or applicator which is adapted to be located within a body cavity to which thermo-therapeutic treatment is to be applied.

One of the objects of the present invention is to provide an improved therapeutic device of this type.

A further object of the invention is to provide an improved therapeutic device of this type which can be actuated from any level with respect to the patient.

15 A further object of the invention is to provide an improved assembly for such a device in which the motor and pumps may be removed as a unit for service and adjustment.

Other objects, advantages and capabilities of 20 the invention will appear from the following description of a preferred embodiment thereof, taken in conjunction with the accompanying drawings, in which

25 Figure 1 is a front elevation of a therapeutic device embodying my invention;

Fig. 2 is a plan view thereof the top cover being removed;

Fig. 3 is a sectional view of the device taken on the line 3—3 of Fig. 1;

30 Fig. 4 is a sectional detail view taken on the line 4—4 of Fig. 3;

Fig. 5 is a sectional detail view taken on the line 5—5 of Fig. 4;

Fig. 6 is a sectional detail view taken on the 35 line 6—6 of Fig. 4;

Fig. 7 is a sectional detail view taken on the line 7—1 of Fig. 4;

Fig. 8 is a sectional detail view taken on the 40 line 8—8 of Fig. 5;

Fig. 9 is a similar view showing the control valve in a different position of adjustment;

Fig. 10 is a fragmentary sectional detail view 45 taken on the line 10—10 of Fig. 2 and adapted to show the location of the heating and heat control units; and

Fig. 11 is a wiring diagram.

Referring to the drawings, the therapeutic device comprises a tank 11, the lower part of which 50 may suitably be of integral drawn metal construction. The tank is provided with a more substantial top plate 12 to which the pan portion may be permanently secured, for example, by soldering. This top plate 12 is provided with a projecting lug 13 at each corner. These lugs rest

upon lugs 14 of corner posts 15 of a casing which surrounds the tank.

The corner posts are provided with end flanges 16 at their upper ends and end flanges 17 at their lower ends. Their lower flanges 17 are connected, 5 for example, by screws to an open base or frame 18 which is preferably provided with resilient feet 19 of rubber, or other suitable material.

At the front of the device an instrument panel 20 of Bakelite, or other suitable insulating material, is screwed or otherwise suitably secured to the front posts 15. An open frame 21 is provided around the panel 20 so as to conceal the screws or means of attachment and to provide a neat finish. 10

At each side the frame 21 is provided with rearwardly extending flanges 22 whereby the frame may be attached to the corner posts 15 at the front of the device. The other three sides of the device are enclosed by a wall member 23 which is suitably bent for this purpose, its central major 20 section extending between the two corner posts 15 at the rear of the machine, and its two extremities extending forwardly so as to underlie the flanges 22 previously referred to, as shown in Fig. 2. The wall member 23 is secured by screws, 25 or other suitable means, to the corner posts 15 at the rear of the device. The flanges 22 and the extremities of the wall member 23 are secured to the front corner posts 15 by the same screws 24.

The housing constituted by the front panel 20 30 and the wall member 23 is completed by a cover 25 which is secured by means of screws to the upper ends of the corner posts 15. The major portion of this cover 25 is horizontal and is spaced substantially above the top plate 12 of the tank 35 11. The cover plate 25 is provided with a large central housing 26 in which the motor, herein-after to be described, is located.

The cover plate 25 is also provided with a pair of vertical elongated housings 27 and 28 which 40 are cut away at the front so as to expose to view the indicating means which they are adapted to receive. The cover plate 25 is provided with an opening 29 through which projects a filling tube 30 carried by the top plate 12 of the tank. This 45 filling tube is normally closed by a removable cap 31. The cover plate 25 is provided with ventilating openings 32, preferably near the base and upper end of the motor housing 26. For conveniently carrying the device, a bail 33 is pivotally 50 secured to the motor housing 26.

Most of the operative parts of the device are mounted upon the top plate 12 of the tank 11, this top plate being provided with openings for the reception of the various devices. The elec-

trical heating unit 34 is enclosed within a tube which is rigidly carried by a plate 35. This plate is mounted on the top plate 12 by means of screws. The effective portion of the heating unit 5 extends through an opening 36 in the top plate 12 into the liquid 37 contained in the tank 11. The heating element 34 is provided with terminals 38 whereby the electrical connections can be made. The device is provided with a thermo- 10 static switch control 39 which is located within a container similarly mounted on the plate 12 and projecting into the liquid in the tank 11. The thermostatic switch 39 can be adjusted by a threaded spindle 40. The interior of the ther- 15 mostatic switch is not disclosed in detail, since many thermostatic switch constructions are known in the art which may readily be employed for this purpose.

The top plate 12 is provided with a large central opening 41 in which the main motor and pump unit is mounted. On one side of this opening is provided a vertical tube 42 through which extends freely the rod 43 of a float 44. At its upper end the rod 43 is provided with a flat head 45.

25 The housing 27 is provided with marks which indicate the appropriate level of the water. It is preferred to provide two horizontal marks slightly spaced, the location of these marks being such that satisfactory liquid level is established 30 when the head 45 lies between them. On the other side of the large opening 41 the plate 12 carries a tube 46 which supports a thermometer 47 with its bulb immersed in the liquid 37. The portion of the stem of the thermometer carrying 35 the readings of the effective range of the device, for example between 100 and 140 degrees F., is exposed in the cut-away portion of the vertical housing 28 into which the upper part of the thermometer projects.

40 The main motor and pump unit will now be described. It comprises a supporting plate 48 which has a marginal flange adapted to rest upon the top plate 12 around the opening 41. It is provided with a central upstanding collar 49 45 which receives the downwardly projecting collar 50 of an electric motor 51. The motor 51 is rigidly secured to the plate 48 by means of a set screw 52 threaded in an opening in the collar 49 and adapted to abut against the collar 50.

50 The shaft of the motor 51 projects downwardly and has mounted thereon near its lower end impellers 53 and 54, these impellers being arranged to operate in a horizontal plane. The impeller 53 may be suitably made of bakelite or other suitable light material, and it comprises a circular plate 55 provided with a square central boss 56 which is keyed, or otherwise rigidly secured, to the extended shaft of the motor. The impeller 53 is provided with a plurality of vertical vanes 57 which may suitably be arranged substantially tangential with respect to the boss 56.

55 The impeller 54 is substantially similar to but considerably smaller than the impeller 53 just described and is likewise rigidly mounted upon the shaft of the motor. It is, however, mounted at a lower level than the impeller 53 and in a different pump compartment, as will hereinafter appear.

60 The housings or compartments in which the impellers 53 and 54 are located, are supported from the plate 48 by means of legs 58, 59, and 60, the location of which are shown in dotted lines on Fig. 2. The leg 60 is solid. The legs 58 and 59 are tubular and serve as conduits for the outgoing and incoming fluid being circulated by the

device. The impeller 53, which may be termed the delivery or pressure impeller, is located within a housing 61 which is preferably integral with the legs 58, 59, and 60. In manufacture it is preferred to make the housing 61 together with these legs as a single casting, and to solder, braze, or otherwise secure the legs at their upper ends to the plate 48. The upper wall of the housing 61 is provided with a central opening 62. At its lower edge the housing 61 is provided with a flange 63 and above this flange it is internally threaded so as to receive a wall 64 which separates the delivery compartment 61 of the impeller 53 from the return compartment 65 of the impeller 54. The wall 64 has a central boss 64', through which the shaft of the motor extends freely, the small amount of leakage between the two pump housings being immaterial. Since the impellers 53 and 54 are quite light there is no tendency for the motor shaft to whip. One advantage of this construction is that I may use a standard motor with an extended shaft and avoid the necessity of providing aligned bearings on separable parts of the assembly.

20 The return or suction housing 65 is preferably 25 in the form of a dish-like casting having a flange 66 whereby it is secured to the flange 63 of the housing 61. The outgoing conduit 58 communicates with the periphery of the housing 61, preferably at a position indicated in dash-and-dot 30 lines in Fig. 6, at the end of a peripheral pocket 67 into which the normal rotation of the impeller 53 throws the liquid. As indicated above, the liquid enters the impeller chamber 61 through the central opening 62. Since it is preferred to 35 have a relatively shallow tank, I provide above this opening a baffle plate 68 which prevents the formation of a vortex and the forcing into the inflatable bag or applicator of any substantial quantity of air. At its upper end the tubular leg 40 58 communicates with a bore 69 which, in turn, terminates at a conical valve seat 70 integrally formed with the plate 48.

25 The hollow leg 59 extends downwardly from a bore 71, which also communicates with the 45 conical valve seat 70, at a position substantially diametrically opposite the point of communication of the bore 69. The bore of the hollow leg 59 is in alignment with a passage 72 formed in the housing 65, which passage extends radially 50 below the impeller 54 and terminates in a wall 73 as the center of the impeller 54, and below this impeller. As best shown in Fig. 7, the housing 65 is provided with a tangential extension 74 on the same level as the impeller 54 so that the 55 impeller 54 throws the liquid drawn in through the bore 59 into the extension 74. The extension 74 projects beyond the flange 63 of the housing 61 so that the discharge liquid is delivered 60 upwardly from the extension 74.

20 A bore 75 communicates with the valve seat 70 in alignment with the bore 69. The bore 75 extends into a boss 76 which is internally threaded for the purpose of receiving a connector 77 of conventional type whereby the bore 75 may 65 readily be connected to a copper tube 78. The copper tube 78 communicates on the rear side of the panel 20 with a cup 79 which is provided with a nipple 80 which extends outwardly from the panel 20. The cup 79 and 70 nipple 80 are mounted on the panel 20 by means of a nut element 81 which is threaded 75 mounted on the nipple 80. The cup 79 is also connected by means of a copper tube 82 to a pressure gauge 83 mounted on the rear of the 75

panel 20 and having an indicating face 84 visible through a conveniently located opening in the panel 20.

Another bore 85 extends into the valve seat 70 in alignment with the bore 71. The bore 85 is provided with a lateral boss 86 which is internally threaded to receive a conventional connecting element 87 whereby the bore 85 is connected to a copper tube 88. The copper tube 88 communicates with a cup 89 which is integral with a nipple 90. The cup 89 and nipple 90 are mounted on the panel 20 by means of a nut element 91.

The conical valve seat 70 receives a conical valve member 92 which is provided with longitudinal grooves 93 and 94 which are adapted to put the bore 69 into communication with the bore 75 and the bore 71 into communication with the bore 85, when the valve member 92 is placed in the appropriate position. The groove 93, which is intended to cooperate with the bores 71 and 85, to control the suction or return of fluid, is much wider, circumferentially of the valve member 92 than is the groove 94 which is intended to cooperate with the bores 69 and 75 to control the delivery of liquid under pressure.

The valve member 92 is provided with a stem 95 which projects forwardly through a suitable opening in the panel 20. In order to keep the valve member 92 firmly in place against the seat 70, the forward end of the seat 70 is internally threaded to receive an annular plug 96. Between this annular plug and the forward end of the valve member 92 is located a coil spring 97, normally held by the plug 96 under substantial compression. The forward end of the stem 95 has rigidly mounted thereon a handle 98 which is adapted to cooperate with two pins 99 on the panel 20, so as to limit the throw of the valve member 92 and maintain the grooves 93 and 94 in exclusive cooperation with the bores 71 and 85 and the bores 69 and 75, respectively. The extreme positions of the valve member 92 are shown in Figs. 8 and 9 and in these figures the hand lever 98 is indicated in dash-and-dot lines. It will be seen that in the position shown in Fig. 8 the grooves 93 and 94 are out of communication with the ducts 71 and 85 and 69 and 75. As the handle 98 is rotated in clockwise direction (Fig. 1), the relatively wide groove 93 establishes communication between the bores 71 and 85 before the groove 94 comes into communication with either of the bores 69 and 75. This condition corresponds to the position "Suction on" marked on the panel 20. The position of the handle 98, shown in Figs. 1 and 8, is indicated in Fig. 1 of the drawing at "Suction off". When the handle 98 is rotated slightly further it reaches a point on the panel 20 which is indicated thereon by the words "Pressure off". As the clockwise rotation of the valve member 92 is continued, the point of the handle 98 approaches the position "Pressure on" which is shown diagrammatically in Fig. 9. In this position the nipple 80 is delivering fluid at a pressure indicated on the pressure gauge 84 and the nipple 90 is withdrawing fluid from the inflatable bag owing to the suction created by the impeller 54.

The spindle 40, by means of which the thermostat 39 is regulated, also projects forwardly through an opening in the panel 20 and has rigidly mounted thereon a handle 100, and the movement of this handle is arrested in its extreme positions by means of a stop 101. Adjacent this handle the panel 20 is provided with an arrow and indicia indicating the direction of

turning of the handle 100 for the purpose of increasing the degree of heat provided by the heating element 34. Also mounted upon the panel 20 are a switch 102 for turning the motor on and off, a switch 103 for putting a resistance 104 in series with the motor to adapt the same for direct current so that the same pumping effects are obtained with both direct and alternating current, and a switch 105 for turning on and off the heat. A lamp 106 is arranged in parallel with the heating unit 34. This lamp is located near a transparent button 107 so that a visible signal is provided indicating to the operator that the heat is turned on.

Current is supplied from any convenient outlet by means of a cable 108. A convenient system of wiring is shown in Fig. 11.

In order to minimize, as far as possible, the objectionable noise of the motor when operating, particularly where a ball bearing motor is employed, I prefer to provide rubber pads 109 between the lugs 13 and 14 and to put rubber bushings 110 around the screws which secure the lugs 13 to the lugs 14. I also provide rubber pads 111 beneath the heads of these screws. This manner of mounting gives a completely yielding and insulated mounting for the tank assembly. In order to prevent noisy vibrations being transmitted to the panel through the pipes 82 and 83, I prefer to provide a gap in these pipes and to connect the spaced ends by means of pieces of heavy rubber tubing 112 and 113, respectively.

As indicated above, the nipples 80 and 90 are mounted on the panel 20 and project forwardly therefrom. These nipples are adapted to receive lengths of heavy rubber tubing 114 and 115 which are, in turn, connected to an applicator 116 of known type. Such applicators are normally formed of rubber of convenient shape for the body cavity for which they are intended and they are normally provided with an internal septum which causes the incoming water to flow to the innermost end and thereafter to return on the other side of the septum to the return nipple 90. One of the important advantages of my invention is that in beginning treatment the suction is first applied to the applicator 116 and with continued rotation of the control 98, liquid under pressure is supplied to the applicator. The impeller 53 being substantially larger than the impeller 54, a certain pressure will be created in the applicator 116 when the motor is running. This pressure will produce a distention of the applicator appropriate for the treatment which is being given and this pressure is substantially less than that which would be produced by the impeller 53 alone. The pressure produced by the impeller 53 alone is sufficient, in some cases, to rupture the applicator, and in other cases to produce an excessive distention thereof which may be dangerous and painful to the patient. The present device avoids any possibility of this dangerous circumstance arising.

During normal use of the machine, the water in the tank 11 is first brought to a comfortable temperature, the applicator 116 is placed in position for the treatment, and the control 98 is turned so as to cause the heated water to circulate through the applicator. The thermostat control 100 is progressively turned in the clockwise direction, as viewed in Fig. 1, so as to produce progressively higher temperatures. As will appear from the description above, the control 100 affects the adjustment of the thermostatic

switch 39 and this switch operates automatically to make and break the circuit of the heating element 34 so as to maintain the water at a substantially constant temperature corresponding to the condition of adjustment of the thermostatic switch 39. It will readily be understood that the temperature of the circulating water can be controlled as desired by the operator, in accordance with the treatment.

10 Although the invention has been described in connection with the specific details of a preferred embodiment thereof, it must be understood that such details are not intended to be limitative of the invention except in so far as 15 set forth in the accompanying claims.

Having thus described my invention, what I claim as new and desire to secure by Letters Patent of the United States is:

1. A therapeutic device of the type described, 20 comprising a tank for liquid to be circulated, means for heating said liquid, and a unitary structure including a flange whereby it is removably mounted on said tank and partly extending thereinto, said unitary structure comprising a 25 motor, a pump adapted to be submerged in said liquid, and conduit means above said flange for supplying heated liquid from and to said pump.

2. A therapeutic device of the type described, 30 comprising a tank for fluid to be heated, a cover for said tank provided with openings, a combined motor and pump unit mounted on said cover and removable as a unit therefrom, part of 35 said unit extending through one of said openings into the fluid in the tank, said unit having an inlet and an outlet for fluid above said cover, a heating unit mounted on the cover and having a part thereof projecting through one of said openings into the fluid in the tank, and a thermostat 40 control for said heating unit mounted on said cover and having a part thereof projecting through one of said openings into the fluid in the tank.

3. A therapeutic device of the type described, 45 comprising a tank for fluid to be circulated, a cover therefor having an opening, means for heating the fluid, a unitary structure comprising a motor, a pump and conduit means for circulating said fluid, mounted on said cover around said opening and removable as a unit therefrom, the 50 motor and the conduit means being located above the cover and the pump below the cover, said conduit means extending from said unit above said cover.

4. In a therapeutic device of the class described, 55 in combination, a motor having an extended shaft, a mounting plate on which said motor is

rigidly mounted, a pair of superposed pump chambers in spaced relation to said plate, posts rigidly securing said chambers to said plate, said shaft extending freely through said chambers, and impellers in said chambers mounted on the 5 free end of said shaft, two of said posts being hollow, one of them being connected to the inlet of one pump chamber, and the other being connected to the outlet of the other pump chamber, the outlet of first said chamber and the inlet of 10 last said chamber being open to the exteriors of the chambers.

5. In a therapeutic device of the class described, in combination, a motor having an extended shaft, a mounting plate on which said motor is 15 rigidly mounted, a pair of superposed pump chambers in spaced relation to said plate, posts rigidly securing said chambers to said plate, said shaft extending freely through said chambers, impellers in said chambers mounted on said shaft, 20 two of said posts being hollow, one of them being connected to the inlet of one pump chamber, and the other being connected to the outlet of the other pump chamber, the outlet of first said chamber and the inlet of last said chamber being 25 open to the exteriors of the chambers, conduits connected to both said hollow posts, and a single valve member controlling communication therebetween, said valve member being adapted to put the first said chamber into communication with 30 its conduit before putting the second said chamber into communication with its conduit.

6. In a therapeutic device of the class described, a motor having an extended shaft, a plate on which the motor is mounted, a pair of pump housings in spaced relation to said plate and posts securing said housings to said plates, two of said posts being hollow, one communicating with the outlet of one pump housing and the other communicating with the inlet of the other pump 40 housing, impellers mounted on said shaft within the housings, the impeller in the last said housing being smaller than the other impeller, a valve seat in said plate, ducts leading into said seat at circumferentially spaced positions and communicating with said hollow posts, ducts connected to external conduits leading into said valve seat, and a valve member provided with grooves adapted to put one of the last said ducts into communication with one pump housing, and the other of last 50 said ducts into communication with the other pump housing, the valve member and its housing being arranged to provide a wider range of such communication for the housing having the smaller impeller.

ARTHUR C. KLECKNER.
